Co., Rockford, Ill., a corporation of Delaware

Filed Sept. 1, 1967, Ser. No. 8,481

Term of patent 14 years

(Cl. D52—3)

FIG. 1.

FIG. 2.

FIG. 3.

FIG. 4.

FIGURE 1 is a front elevational view of a coin box door front for vending machines or the like, embodying my new design;

FIG. 2 is a side elevational view thereof;

FIG. 3 is a top plan view thereof; and

FIG. 4 is a cross sectional view thereof taken on the line 4—4 of FIG. 1.

The broken line representation of a locking means in FIGS. 1 and 4 is for purposes of illustration only.

I claim:

The ornamental design for a coin box door front for vending machines or the like, substantially as shown and described.
